UNITED STATES PATENT OFFICE.

MARTIN S. RUNSVOLD, OF SAN DIEGO, CALIFORNIA.

STEEL-PULLER.

1,286,422.

Specification of Letters Patent.

Patented Dec. 3, 1918.

Application filed February 1, 1918. Serial No. 214,917.

To all whom it may concern:

Be it known that I, MARTIN S. RUNSVOLD, a citizen of the United States, and a resident of San Diego, in the county of San Diego 5 and State of California, have invented certain new and useful Improvements in Steel-Pullers, of which the following is a specification.

My invention is an improvement in steel 10 pullers, and has for its object to provide mechanism of the character specified for pulling jammed steels from drill holes, wherein means is provided for engaging the drill and the face of the drift, and for withdrawing the steel from the drill hole.

In the drawings:

Figure 1 is a top plan view of the improved puller in place;

Fig. 2 is a longitudinal section;

20 Figs. 3, 4 and 5 are sections on the lines 3—3, 4—4 and 5—5, respectively, of Fig. 2, each view looking in the direction of the arrows adjacent to the line.

The present embodiment of the invention 25 is shown in connection with the drill steel 1 of usual construction, having the longitudinally extending grooves 2 spaced at intervals of ninety degrees with respect to each other. A shell 3 is provided, adapted to be slipped over the stem, and having at one end an outwardly extending tapering flange 4 forming a foot, for engaging the face of the drift, as shown. This shell is internally threaded, and within one end is engaged a 30 screw 5, the said screw having a reduced portion 6 extending outside the shell at the end remote from the foot, and an annular shoulder 7 is formed between the reduced portion and the body of the screw. This 35 screw has a central opening for receiving the stem and is adapted to fit over the same. A collar 8 is connected to the shell at the end remote from the foot, and this collar engages the shoulder 7 to prevent movement of the 40 shell with respect to the screw in one direction.

A pair of dogs 9 is pivotally connected 45 with the screw 6 near its outer end, the said screw having longitudinally extending slots 50 or recesses 10 for receiving the dogs, and each of the arms is in the form of an elbow lever consisting of two arms extending at an acute angle with respect to each other. The arms are pivoted in the recesses 10, and 55 the short arm of each dog is adapted to en-

gage within one of the grooves 2 of the steel and to grip the bottom of the groove, as shown in Fig. 2, when the long arms of the dogs are pressed toward the steel. These arms extend alongside the steel and they are 60 beveled on their inner faces adjacent to the steel.

A nut 11 is threaded on to the screw at the end adjacent to the dogs, and the bore of the screw at the end adjacent to the dogs is 65 reamed, as shown in Fig. 2, and engages over the dogs. It will be evident that when the screw is turned toward the shell 3 the dogs will be constrained to grasp the steel within the slots, and when the screw is 70 turned the steel will be turned therewith.

The dogs are engaged with the grooves 2, and it will be evident that when the nut 11 is turned toward the shell the dogs will be caused to grasp the steel in the bottoms of 75 the grooves. An ordinary wrench 12, in common use in mines, is engaged by the steel, and with the parts in the position of Fig. 1, the steel is turned. The screw is gradually turned down in the shell away 80 from the face of the drift, and the steel is withdrawn. A collar or plug 13 is threaded into that end of the shell adjacent to the face of the drift, to prevent the entrance of dirt and the like that might injure the 85 threads of the shell or screw.

It will be understood that while the dogs are described and shown as adapted for grasping pipe, they could be also shaped to grasp different kinds of steel, such as round, 90 hexagonal, plain or grooved.

I claim:

A device of the character specified, comprising an internally threaded shell, a screw having a longitudinal axial opening for permitting the shell and screw to be slipped over the steel, a pair of dogs pivoted to the screw on an axis transverse to that of the screw for engaging the steel to clamp the same to the screw to constrain the steel to 95 turn and move longitudinally with the screw when the steel is turned, each dog consisting of a short arm adapted to engage the steel and a long arm extending longitudinally of the axis of the screw, and a sleeve for engaging the said long arms to move the short arms into gripping engagement with the screw.

MARTIN S. RUNSVOLD.
